BILLFOLD

Clarence Leslie Green, Albuquerque, N. Mex.

Application February 28, 1940, Serial No. 321,319

6 Claims. (Cl. 150—38)

This invention relates to a fold for carrying papers and more particularly to a billfold adapted to receive bills of several different denominations.

In the prior art, billfolds have been suggested having a main pocket to receive a number of groups of bills of different denominations with all bills of the same denominations in separate groups and having openings in the walls of the fold through which bills from a single group could be withdrawn.

It is a particular object of this invention to provide an improved billfold of this type having openings in one wall thereof.

Another object is to provide such a billfold having openings cooperating with a plurality of separate compartments so that individual bills disposed in the compartments may be withdrawn.

It is another object of this invention to provide an arrangement of openings that will provide an immediate indication by this disposition, which compartment is being opened.

It is another object of this invention to provide a more compact fold having openings all on one wall communicating with the various compartments.

Other objects and advantages of the invention will be apparent from a consideration of the following description of the illustrative embodiment shown in the accompanying drawing, in which:

Figure 1 is an elevation of the billfold showing the arrangement of the flaps on the inside or front face of the fold;

Figure 2 is a sectional view taken on line 2—2 of Figure 1;

Figure 3 is a detailed view of the flap arrangement shown on the left-hand end of the billfold of Figure 1, disclosing the flap covering the opening to one of the groups of bills turned down;

Figure 4 is a view similar to Figure 3 showing the flap communicating with another of the groups of bills turned down, and

Figure 5 is a view similar to Figure 3 showing the flap communicating with still another of the groups of bills turned down.

The present embodiment of the invention discloses a billfold made of leather or other suitable flexible material having a front wall 10 and a rear wall 11 best shown in Figure 2. These walls are fastened together in any well-known manner to provide a pocket into which bills may be inserted. The pocket has a single entrance opening through which the bills are inserted, the entrance being closed by means of the "zipper" 12.

12 shown in Figure 1. The main pocket is divided into a plurality of individual compartments 14, 15, 16, 17, and 18 by means of partitions 20, 21, 22, and 23, and each compartment is constructed to receive a particular group of papers or bills.

The compartment 14, for example, may be, and preferably is, utilized for bills of a particular denomination, and as indicated, a plurality of \$20 bills may be placed in this compartment. At the right-hand end of the compartment 14, as shown in Figure 2, an opening 25 is provided which may be covered by a flap 26. The flap has suitable snap connection with the fastener 27 on the body 10 of the billfold so that the flap may be held in closed position over the opening.

The next compartment 15 may be filled with \$10 bills, and the left-hand end of this compartment, as shown in Figure 2, has an opening 30 communicating therewith, this opening being best shown in Figure 5. The opening 30 is covered by a flap 31 having a cooperating snap fastener 32.

Compartment 16 may be provided for \$5 bills, 25 and it has an opening 35 at the left-hand end of the billfold, as best shown in Figure 4. A flap 36 covers this opening, and a snap fastener 37 maintains the flap in closed position.

The compartment 17 may be provided for \$1 bills, 30 and this compartment has an opening 40 disposed at the left-hand end of the billfold, the opening 40 being covered by a flap 41, as shown in Figure 3. The flap 41 has a snap fastener 42 to maintain it in closed position.

35 The compartment 18 at the rear is completely closed, and valuable papers, such as bills of large denominations or deeds, notes, etc., may be secretly carried therein.

The billfold may be provided with the usual 40 identification, receiving means 45, and another pocket 46 on its front face to receive cards.

After the bills have been segregated into their individual groups and inserted in the various compartments through the entrance opening, the billfold may be closed by "zipper" 12. In order thereafter, to withdraw bills from the fold, it is merely necessary to open the flap communicating with the compartment holding the bills of the proper denomination. Due to the partition between the compartments, any number of bills can be withdrawn from a single compartment without disturbing any of the bills of different denominations.

The arrangement with the three openings 30, 55 35, and 40 and their associated flaps all at one

end of the billfold provides a very compact arrangement wherein the various groups of \$1, \$5, and \$10 bills may be arranged with one substantially directly behind the other. The construction is such that the rearmost group may be reached without exposing either of the two foremost groups. It is also to be noted that either one of these three groups may be reached through its cooperating opening for the removal of bills without revealing the other groups.

In the construction shown, the flap 41 is hinged at the extremity of the pocketbook and is snapped over the bills, as is clearly shown in Figure 3, while the other flaps 31 and 36 covering the openings to the \$10 and \$5 bills, respectively, snap shut to the extreme end of the billfold and hinge about the edge 43 of opening 40 (see Figure 3). It is seen that the flaps 31 and 36 include a portion of the partitions 22 and 23, respectively, and flap 41 forms a portion of the front wall 10 of the billfold.

The arrangement of the flaps and openings is such that there is a single opening for \$20 bills at one end of the pocketbook and three openings for bills of the lower denominations disposed at the other end of the fold. Such a construction immediately appraises the owner which denomination bill is being withdrawn merely from feeling the pocketbook to determine the arrangement of the openings. Either the three openings at one end or the single opening gives such an indication. Thus, it is possible to withdraw a particular bill without seeing the pocketbook, and in certain circumstances this is a very valuable feature. In the preferred construction, the single flap at one end for \$20 bills is suggested, because, being set apart, the user is immediately reminded of the importance of opening this flap. However, it is evident that if all the flaps were placed at one end, a design could be originated, within the concept of the present invention, to indicate which flap covered a particular compartment.

In the preferred construction of the pocketbook a flap 45 is provided having a snap fastener adapted to fasten onto the means 46 to hold the billfold in folded position.

Various modifications of the invention herein disclosed may appear to those skilled in the art, and, therefore, the invention is not intended to be limited by the disclosure herein contained other than by the following claims.

I claim:

1. A billfold having a front wall and a back wall secured together to form a pocket to receive bills of different denominations, coextensive partition means in said pocket to provide a plurality of walled compartments, whereby when the bills are arranged in groups with all of the bills of the same denomination in a single group they may be disposed in the pocket with each group in a separate compartment, said billfold having an opening in one of said walls disposed at the end thereof, certain of said partition means extending across said opening and having an outer end releasably fastened to the other of said walls, end flaps to permit access to each of said compartments, at least one of said flaps being formed of said extending portion of said partition means.

2. A billfold having a front wall and a back wall secured together to form a pocket to receive bills of different denominations, coextensive partition means in said pocket to provide a plurality of walled compartments, whereby when

the bills are arranged in groups with all of the bills of the same denomination in a single group they may be disposed in the pocket with each group in a separate compartment, said billfold having an opening in one of said walls disposed at the end thereof, certain of said partition means extending across said opening and having an outer end releasably fastened to the other of said walls, overlapping end flaps to permit access exclusively to each of said compartments, at least one of said flaps being formed of said extending portion of said partition means.

3. A billfold having a front wall and a back wall secured together to form a pocket to receive bills of different denominations, coextensive partition means in said pocket to provide a plurality of non-communicating walled compartments, whereby when the bills are arranged in groups with all of the bills of the same denomination in a single group they may be disposed in the pocket with each group in a separate compartment, said billfold having an opening in one of said walls disposed at the end thereof, certain of said partition means extending across said opening and having an outer end releasably fastened to the other of said walls, end flaps to permit access to each of said compartments, at least one of said flaps being formed of said extending portion of said partition means.

4. A billfold having a front wall and a back wall secured together to form a pocket to receive bills of different denominations, coextensive partition means in said pocket to provide a plurality of non-communicating walled compartments, whereby when the bills are arranged in groups with all of the bills of the same denomination in a single group they may be disposed in the pocket with each group in a separate compartment, said billfold having an opening in one of said walls disposed at the end thereof, certain of said partition means extending across said opening and having an outer end releasably fastened to the other of said walls, overlapping end flaps to permit access exclusively to each of said compartments, at least one of said flaps being formed of said extending portion of said partition means.

5. A billfold having a front wall and a back wall secured together to form a pocket to receive bills of different denominations, coextensive partition means in said pocket to provide a plurality of walled compartments, whereby when the bills are arranged in groups with all of the bills of the same denomination in a single group they may be disposed in the pocket with each group in a separate compartment, said billfold having an opening in one of said walls disposed at the end thereof, certain of said partition means extending across said opening and having an outer end releasably fastened to the other of said walls, end flaps to permit access to each of said compartments, at least one of said flaps being formed of said extending portion of said partition means, said billfold having an opening in the opposite end of said wall to permit access to one of said pockets, and a flap for covering said last-named opening.

6. A billfold having a front wall and a back wall secured together to form a pocket to receive bills of different denominations, coextensive partition means in said pocket to provide a plurality of walled compartments, whereby when the bills are arranged in groups with all of the bills of the same denomination in a single group they may be disposed in the pocket with each

group in a separate compartment, said billfold having an opening in one of said walls disposed at one end thereof, certain of said partition means extending across said opening and having an outer end releasably fastened to the other of said walls, overlapping end flaps to permit access to each of said compartments, at least one

of said flaps being formed of said extending portion of said partition means, said billfold having an opening in the opposite end of said wall to permit access to one of said pockets, and 5 a flap for covering said last-named opening.

CLARENCE LESLIE GREEN.
